UNITED STATES PATENT OFFICE.

JOHN W. CUBBAGE AND JOHN ALEXANDER, OF GALLIPOLIS, OHIO.

IMPROVEMENT IN MOP-HOLDERS.

Specification forming part of Letters Patent No. **181,415**, dated August 22, 1876; application filed May 16, 1876.

To all whom it may concern:

Be it known that we, J. W. CUBBAGE and JOHN ALEXANDER, both of Gallipolis, Gallia county, Ohio, have invented an Improved Mop-Holder, of which the following is a specification:

The drawing represents, in Figure 1, a side view, and in Fig. 2 a section, of our mop-holder.

The invention will first be described in connection with the drawing, and then pointed out in the claim.

A represents the handle; E, a wire bent twice at right angles, and having arms that pass through holes in the ends of a plate or clamp-bar, F. The arms of wire or clamp-rod E are bent inward as well as upward, and their ends are attached to a socket, G. Through the latter passes the end of handle A, the socket being secured thereto by a hand-screw, g'. The cloth is placed between the middle

part of clamp rod or frame E and clamp-bar F, the handle being then inserted in the socket or sliding head G, and its end pressed down against clamp-bar F. This clamps the cloth very securely between the bar and rod, while, the clamp-screw g' being then tightened, the parts of mop-head are locked together.

What we claim as new is—

The mop-holder herein described, consisting of the sliding-head G, clamp rod or frame E, clamp-bar F, set-screw g', and handle A, the clamp-rod E being secured at its ends in the sliding head, and fitted to be adjusted upon and secured to handle A, as and for the purpose specified.

JOHN WILLIAM CUBBAGE.

JOHN ALEXANDER.
